UNITED STATES PATENT OFFICE.

ALEXANDRE MURINICK, OF ST. PETERSBURG, RUSSIA.

BURNER FOR INCANDESCENT GAS-LIGHTING.

SPECIFICATION forming part of Letters Patent No. 650,858, dated June 5, 1900.

Application filed November 27, 1899. Serial No. 738,426. (No model.)

To all whom it may concern:

Be it known that I, ALEXANDRE MURINICK, merchant, of 47 Mokhovaia, city of St. Petersburg, Empire of Russia, have invented a new 5 and useful Burner for Incandescent Gas-Lights, of which the following is a specification.

The subject of the foregoing invention is a new burner for incandescent gas-lighting; 10 and the invention has for its object to provide a burner in which the flame will be independent of fluctuations in the gas-pressure, the latter being regulated at the burner as desired, the pressure damage to the mantle 15 is reduced to a minimum, and a more complete mixture of gas with the necessary quantity of atmospheric air may be accomplished.

In general it should be remarked that in the absence of means for the accurate regulation of the flow of gas in burners of this 20 type the action is very unsatisfactory, owing to fluctuations in pressure in the supply of gas. The regulation of the flow of gas is accomplished with facility and exactness in my 25 improved construction of burner.

One embodiment of my new burner is illustrated in the accompanying drawings, in which—

Figure 1 is a longitudinal section. Fig. 2 30 shows the arrangement of the nozzle on an enlarged scale, and Fig. 3 is a plan view of the same.

More specifically, the arrangement is as follows: A special form of body *a* carries at its 35 upper end a sieve-like cap *b*, which is supported by a tube *c*, provided with a number of slits on its upper end, so that the incandescent-mantle rod *e* may be clamped in a well-known manner by means of the screw-nut *d*, arranged upon said tube. The body *a* is secured at bottom through the medium 40 of a bayonet-joint in a ring *g*, which is provided at the bottom with a screen-disk *s* and is connected at several points with a cup *i* through the medium of springs *h*. This cup *i* is provided with a number of air-holes *k* and with a support *n*, secured thereto through the medium of the nut *m*. Said support, as 45 will be seen in Fig. 2, is provided with an internal thread, so that a nozzle *o* may be screwed therein. The nozzle is provided with several vertical bores *v*, emerging in a plane

below the apex, and through these bores the gas escapes. From the foregoing it is obvious that the point of the nozzle is closed. 55 The same can be made to approach or recede from the opening *p*, formed in the support *n*, so that this opening *p* may be made larger or smaller at will. The direction and location of the 60 bores *v* are such that flow of gas is directed and distributed around the periphery of the cone, and this assists the gas in its further passage to move in a uniform ring, which results in the advantage that the outer and inner 65 walls of the hollow cylindrical body of gas thus formed obtains much greater opportunity than if otherwise constructed to mix itself with the enveloped atmospheric air. The nozzle *o*, moreover, as is evident from 70 Fig. 2, is likewise provided with internal threads, so that the entire burner may be screwed upon any gas-fixture *A*, as may be desired.

The operation is as follows: If the pressure 75 in the gas-pipe is very great, the flame may in consequence burn above the incandescent mantle. In order to prevent this, the screw 2 is loosened and the support *n* is screwed downward. The opening *p* will thus become 80 smaller and the escape of the gas more restricted. This position of the nozzle can be fixed by the screw 2 so that a uniform burning of the flame will thereafter be obtained. If, however, the gas-pressure is smaller, the 85 support *n* will be screwed upward, whereby the opposite conditions prevail—that is to say, the opening *p* will be greater. It should be added that following the escape of the gas through the opening *p* into the cup *i* an immediate mixture of the air takes place, which 90 will be still further essentially advanced in the lower part of the body *a*. The mixture then, as shown by the arrows, arrives in a thoroughly-mingled condition at the mantle. 95

Having thus described my invention, the following is what I claim as new therein and desire to secure by Letters Patent:

1. A burner for incandescent gas-lights comprising the hollow body *a* which receives 100 the incandescent mantle at the upper end thereof, the support *n* for said body, provided with the central aperture and the nozzle projecting into said aperture, adjustable to and

from the latter to regulate the escape of gas therethrough and provided with a plurality of vertical channels distributed around and emerging from the nozzle in a plane below its apex; substantially as set forth.

2. An incandescent gas-burner comprising the hollow body *a* adapted to receive the mantle at its upper end, the support for said body provided with a gas-passage centrally beneath the same, the cup *i* constructed for the admission of air, interposed between the body and the support and the nozzle *o* having its apex entering the gas-passage in the support and adjustable to and from the latter to regulate its area, and a plurality of gas-bores distributed in the nozzle emerging from its sides below the said passage.

3. In an incandescent gas-burner the com-

bination of a nozzle having threads for connecting with a fixture, with external threads, and with longitudinal bores terminating short of its apex, a cylindrical support formed with a centrally-perforated top into which the nozzle projects, and screwed upon the external threads of the nozzle to permit relative adjustment of the parts thus connected, the cup *i* secured upon the upper end of the support and provided with air-inlets and the body *a* supported by said cup.

In testimony that I claim the foregoing as my invention I have signed my name in presence of two subscribing witnesses.

ALEXANDRE MURINICK.

Witnesses: PAUL SCHULZ, ANTON LIPPERT.
